UNITED STATES PATENT OFFICE.

JULIUS WEZEL, OF LEIPSIC, GERMANY.

SMOKE-CONSUMING FURNACE.

SPECIFICATION forming part of Letters Patent No. 608,739, dated August 9, 1898.

Application filed November 22, 1897. Serial No. 659,455. (No model.)

To all whom it may concern:

Be it known that I, JULIUS WEZEL, a subject of the King of Saxony, and a resident of Leipsic, in the Kingdom of Saxony, Germany, 5 have invented certain new and useful Improvements in Smoke-Consuming Furnaces with Inclined Grates, of which the following is a full, clear, and exact description.

The present invention relates to improvements in furnaces having inclined grates divided into several steps, by means of which combustibles which develop great heat may be burned advantageously—*i.e.*, free of smoke and without damaging the grate—and in order to render the present invention more easily intelligible reference is had to the accompanying drawings, in which—

Figure 1 is a longitudinal section of the furnace; Fig. 2, a plan of same, partly broken away; Fig. 3, a vertical section of the middle damper; Fig. 4, a plan thereof; Fig. 5, a detail view of a poker to be used for said damper; Fig. 6, several combined grates of the kind as shown in Fig. 1.

25 A good draft is attained by arranging the flue-openings immediately behind the grate without leaving any intermediate space, said flue slanting upwardly from the end of the fire-bars *d*, as shown at *f*, Fig. 1, the part 30 forming the bridge. Thus the gases of combustion are immediately led off in their natural direction without hindering the air-feed through the grates *a*, *b*, and *d* and the damper *C*.

35 The grate may be constructed, as shown in Fig. 6, with more steps, so that the coal will be forced to pass two or more grates *b* *c*, Fig. 6, before it is completely consumed. Between the grates *b* and *d* and *a* and *b*, Figs. 1 and 40 2, and *c* and *d*, *b* and *c*, *a* and *b*, Fig. 6, respectively, a cooling-pipe system *D*, *D'*, and *D''* may be arranged, through which a continuous current of cold water is fed from the pipe *E*, the heated water of the system being 45 led off in a suitable manner at *F* and applied to any desired purpose.

The cold water enters at *D*, is transmitted to *D'*, and from *D'* to *D''*, respectively, and therefrom led off at *F*.

50 The pipes *D*, *D'*, and *D''* are arranged im-

mediately under the heads of the grate-bars *b*, *a*, and *c*, respectively, crossing under the grate and cooling the latter at these parts.

The draft of the air to the fire is increased by the cooling influence of the tubes. 55

The fire is worked in the following manner: Before fresh fuel is introduced at *A* the material burning on *b* or *b* and *c* at the doors *B* and *B'*, respectively, is pushed forward in the direction of *d*, and thus the fuel on grate *b*, 60 being in the first stage of combustion, is pushed down one step of the grate. In order to effect this properly, the doors *B* or *B'*, respectively, Fig. 6, which on removing the fire must be fully opened, are provided with 65 openings *m*, which may be closed by sliding plates *h*.

The openings *m* are opened by means of the poker, Fig. 5, the end *k* of which poker is introduced into the fire, but no farther 70 than the collar *n*, thus preventing burning fuel from being moved too far forward, but enabling sufficient movement of the same to cause it to pass from the grate *b* or *b* and *c*, respectively, to the grate *d* as thoroughly- 75 consumed material, where it mixes with the air previously heated on its way through the grate and burns away, forming smokeless combustion-gases.

For observing the fire at the dampers *B* *B'*, 80 Figs. 1, 2, and 6, the same are provided with suitable peep-holes, Figs. 3 and 4, which remain always open. The arrangement of the said dampers as described obviates the necessity of opening of same on raking the fire, and 85 thus the falling out of fuel and the entrance of superfluous air is provided against.

The device may be employed in connection with other inclined grates and can of course be carried out in any desired manner. 90

I claim as my invention—

1. In a furnace the combination of a series of stepwise-arranged inclined grates, having doors interposed between the steps, a water-pipe system extending around and between 95 the steps, peep-holes and orifices through which to insert the fire-irons and means for preventing the fire-irons from being inserted too far into or between the steps, substantially as described. 100

2. In a furnace the combination of a series of stepwise-arranged inclined grates, having doors interposed between the steps, a water-pipe system extending around and between the steps peep-holes and orifices through which to insert the fire-iron and a fire-iron having fast thereon a collar for the purpose substantially as described.

In testimony whereof I have signed my name to this specification in the presence of two subscribing witnesses.

JULIUS WEZEL.
